UNITED STATES PATENT OFFICE.

REGINALD C. THOMAS, OF BROOKLYN, NEW YORK.

ASH TRAY AND CIGAR EXTINGUISHER.

Application filed October 16, 1925. Serial No. 62,709.

The invention relates to a two part article, with the parts designed to function, respectively, as an ash tray and a cigar extinguisher, and which two parts are designed 5 to be assembled with the cigar extinguisher part secured to the ash tray part so as to constitute a base supported unitary article of manufacture.

The primary object of the invention is 10 to provide a neat, simplified and inexpensive form of receptacle for receiving, holding, extinguishing the lighted end of one or more cigars introduced into the same and which will additionally function as a receptacle for receiving ashes flicked from the cigar while in use and for receiving the ashes and cigar butts after the latter has been extinguished.

In this specification and in the annexed 20 claims the expression "cigar" is used in a generic sense to indicate the conventional full size cigar, small size cigar, cigarettes and similar preformed smoking products.

With the intent of preventing a lighted 25 cigar from smothering and smoking when removed from the smoker's lips, it has been suggested heretofore to extinguish the lighted end by a crushing action usually by inserting the lighted end between powerfully actuated crushing jaws which function with 30 varying degrees of crushing effect by the act of the operator pressing some form of manually actuated lever or handle controlling the crushing jaws. Any crushing action 35 however obviously destroys not only the burning end but also the adjacent unlit portion of the cigar and in most cases the cigar as an entirety is crushed or so badly distorted as to prevent it from being again 40 used. It frequently happens that a smoker desires to lay the cigar aside for a moment with the intent of relighting it and continuing the smoke. This of course is impossible 45 with the known form of extinguishers of the crushing type.

Accordingly, one of the features of the present disclosure is to provide for the extinguishing of the lighted end by a gentle, pressing, smothering action which will extinguish the lighted end more by shutting 50 off the free access of combustion supporting air than by any mutilating action resembling a crushing effect. It is apparent that any pinching or smothering action which 55 must be gentle in its working to attain the object herein featured, would have to be

designed to compensate for the difference in size or diameter of the different types of cigars which it is designed to accommodate. For instance, with a small diametered, frail 60 article like a cigarette, a weak pinching of the lighted end is all that is required, and any greater action would crush the cigarette while with a larger object such as a full size cigar any weak pinching effect would not 65 be effective in that the large size cigar would resist the light pinching action of weak jaws and would of course continue to smoke.

Accordingly, another object of the invention is to provide a form of extinguisher mechanism which will be controlled more or less automatically by the type of cigar introduced thereto and which will function irrespective of the large or small size of the 75 introduced cigar to extinguish the same by smothering action without materially distorting the same.

Another object of the invention is to provide an extinguisher which will not be actuated in the intensity of its pinching or squeezing operation by any manual control 80 on the part of the operator, and in this way to avoid any tendency of the operator inadvertently crushing the cigar incidental to 85 extinguishing the same.

This phase of the invention is attained by forming the extinguisher of two smothering plates adapted to receive the cigar therebetween and which plates are moved into 90 their open operative position solely by the introduction of the cigar therebetween, and in which the opening movement of the plates are resisted by the progressive introduction of springs disposed so that with increased 95 angularity of opening a progressively increased degree of resistance is introduced to such opening movement.

Another object of the invention is to provide an extinguisher of the type outlined in 100 which the previously extinguished cigar is automatically discharged from the extinguisher and permitted to drop into the ash receptacle therebelow incidental to the introduction of the next succeeding cigar into 105 the extinguisher.

It is quite common with ash trays of the open top type that when the ashes are flicked or knocked off the end of the lighted cigar there is a tendency for the ashes to be scattered about the vicinity.

Another object of the invention herein

disclosed is to provide a type of open top ash tray in which there will be a tendency for local draughts to be directed across the same in such way as to carry the ashes to 5 the center of the ash tray and beneath the extinguisher and in this way minimize any tendency for the same to scatter about the room.

Another object of the invention is to provide a structure which will be ornamental and of pleasing appearance and which can be readily constructed with die operations, and which will feature an arrangement of parts so that when demounted ready access 15 is attained to all parts for cleaning and repairing.

Various other objects and advantages of the invention will be in part obvious from an inspection of the accompanying drawings 20 and in part will be more fully set forth in the following particular description of one form of device embodying my invention, and the invention also consists in certain new and novel features of construction and combination of parts hereinafter set forth and claimed.

In the accompanying drawings:—

Figure 1 is a plan view looking down upon a preferred embodiment of the invention 30 with the two parts assembled;

Figure 2 is a transverse sectional view taken on the line 2—2 of Figure 1 looking in the direction indicated by the arrows;

Figure 3 is a similar view taken on the line 3—3 of Figure 1 looking in the direction of the arrows; and

Figures 4 and 5 are detailed explanatory views showing, in Figure 4 the position of the extinguisher with a small size cigar or 40 cigarette in position and in Figure 5 showing the extinguisher with a large size cigar in position.

In the following description and in the 45 claims, parts will be identified by specific names for convenience of expression but they are intended to be as generic in their application to similar parts as the art will permit.

There is shown in the several figures a two-part assembly, one part comprising a 50 bottom supported receptacle 10 constituting an ash tray and designed to receive ashes and cigar butts admitted either directly thereto, or received through a centrally disposed combined chute and extinguisher 11 55 constituting the other part of the completed assembly.

The ash tray 10 is somewhat H-shaped in plan comprising a central portion 12 and two wing portions 13 and 14. Opposite ends 60 of the wing portions have their tops closed by means of a saddle 15 for supporting the cigars in a horizontal position, as is usual in such constructions. The top portion of the wings between the saddle are open as 65 shown at 16 to provide access to the ash tray

when the extinguisher 11 is in position thereon as shown in the several views of the drawing.

The extinguisher 11 has an upper portion 17 constituting a chute rectangular in horizontal cross section. Two opposite walls 18 and 19 of this chute are continued below the upper chute forming portion 18 and have their lower ends turned back upon themselves to form a pair of hollow outstanding 70 feet 20 and 21 substantially square in cross section as shown in Figure 3 and by means of which the extinguisher may be supported independently of the ash tray, and which feet 75 coact with the ash tray to provide a wide-spreading base for the assembly as a whole. The depending portion of the walls 18 and 19 have a spring clutching grip on the central portion 12 of the ash tray 10, so that the assembly as a whole may be lifted or moved 80 from place to place by handling the upper chute part.

The other two sides 22 and 23 (see Figure 2) forming the ash chute have their lower ends outwardly and downwardly flared to 90 form a pair of air deflectors 24 and 25 disposed, when the two parts are assembled as shown in Figure 2, to be positioned within the corresponding wings and to face the opening 16 at the top of the associated wing. By 95 this construction it is seen that air blowing against the side of the chute will be deflected by the baffle on that side to form a gentle whirl within the ash receiving space therebelow in the associated wing and there will be a resulting tendency of any loose ashes 100 to collect in the center of the ash tray beneath the superposed extinguisher 11.

The extinguisher is formed of two depending jaw plates 26 and 27 coacting to 105 form the fire extinguishing feature of this disclosure. The plates are pivoted along their upper edges respectively on pivot pins 28 and 29 the ends of which pins are received in recesses 30 in the side walls 18 and 19 as 110 shown in Figures 4 and 5. The upper edges of these jaw plates are lapped back upon themselves to form hinge connections with their associated pivot pins. The upper portions of the plates are curved from their 115 pivotal edges towards each other to form an upper convexed portion 31 and a lower substantially straight vertically depending portion 32. These plates coact to form at their upper portions a V-shaped, or perhaps more accurately described, a Y-shaped passageway 33 for receiving the lighted ends of the cigars. The lower portions of these jaw plates coact to form a narrow, vertically disposed choke passageway 34 discharging at 120 its lower end 35 into the ash receptacle. When normally disposed each of the plates is in light bearing contact with the free end of a leaf spring 36 and this spring is backed by a second leaf spring 37, the free end of 125 130

which is disposed in the path of movement of the spring 36 and both of which springs are secured at their upper ends by fastening the same to the upper portion of the walls 5 22 and 23 as indicated at 38. It is noted that these jaw plates are free of any manually actuated control medium and are restored to their normally closed, inoperative position solely by the action of the backing 10 springs.

In operation and assuming first that it is desired to introduce into the extinguisher a small size cigar or cigarette with its lighted end pointing downwardly as shown in 15 Figure 4, it is appreciated that the cigarette may be gently forced downwardly and vertically between the rounded faces of the jaws forming the extinguishing clamp. As the small size cigar or cigarette illustrated 20 has a relatively small diameter the jaw forming plates will be moved into open position as shown in Figure 4, this movement being resisted by the tension of the relatively light, frail spring 36. If the operator 25 desires to be especially careful that the cigar be not mutilated he can, in the act of inserting the cigar, cause his fingers to bear on the rounded faces 31 to move them apart, then insert the cigar and gently release the finger 30 pressure on the jaw plates. This will permit the plates to close in gently on the cigar, after which it may be withdrawn either with or without releasing the spring tension on the jaw plates.

35 However, should a large size cigar be introduced, as is shown in Figure 5, the jaw plates will be moved to a greater extent of open position and in this way the opening movement of the plates will be resisted by 40 the combined effect of the two springs. It is obviously within the scope of the invention to multiply the number of springs which should oppose the successive stages of opening movements of the jaw so that it may be 45 resisted by the sequential action of springs of progressively greater rigidity.

In either case the cigar is held with that degree of tension which will be sufficient to pinch and thus extinguish the lighted cigar 50 held therebetween but which will not be so intense in its pinching effect as to materially crush the lighted end or in any other way distort the same so that it cannot be re-lighted or reused.

55 The long narrow passageway 34 below the lighted end of the cigar apparently forms a choke passageway which does not permit free access of combustion supporting air, and the lighted end is thus extinguished more by the 60 act of shutting off the air supply than by crushing the end of the cigar. As noted in Figures 4 and 5 the pinching action is confined to the extreme lighted end and there is no need of introducing the cigar further 65 into the jaw unless it is desired to discard

the cigar in which case it will be shoved further down between the jaws.

In order to discharge the cigar through the extinguisher into the ash tray it is simply necessary for the operator to push 70 with his fingers on the rounded surfaces 31 or in introducing another cigar, the incidental pressing of the fingers on the curved upper faces of the jaws or the incoming cigar in opening the jaws will permit the previously inserted cigar positioned therebetween to drop through the chute passageway 75 34 into the ash tray therebelow.

When it is desired to empty the device it is most convenient to lift the extinguisher 80 bodily from the ash receptacle separating the two parts against the clamping effect of the lower end of the sides 18 and 19. When separated there is provided a wide open top to the receptacle from which the ashes may 85 be readily dumped, all the parts cleaned and the extinguisher reassembled to form the completed article.

The squared feet 20 and 21 may be utilized to receive the tubular portion of a conventional form of upstanding cardboard match box as is usual in such constructions and as suggested in ghost outline in Figure 3.

Having thus described my invention, I 95 claim:—

1. An ash tray including a central portion and a pair of wing portions to form the tray H-shape in plan, a cigar extinguisher including an upstanding ash chute including 100 opposed sides fitting across the central portion of the tray and held from movement horizontally of the cross portion of the H-shaped tray by the wing portions, the central part of each wing portion being open at top, and cigar saddles carried by the 105 wing portion at opposite sides of the adjacent opening and acting to close opposite ends of the tops of the wing portions.

2. A combined ash tray and cigar extinguisher comprising an open top base supported ash receptacle, an ash chute supported centrally on top of said receptacle and provided with an opening discharging into the receptacle, incompletely closing the top thereof to form an air port on one side of 110 the chute, and an air deflector plate carried by the ash chute extending downwardly, inclined away from the same and disposed in the ash receptacle facing said opening to cause incoming air currents to sweep the 115 ashes towards the central portions of the receptacle.

3. A combined ash tray and cigar extinguisher comprising a base supported ash receptacle, a readily removable unit de- 120 mountably fitted to the receptacle, constituting an ash chute discharging into the receptacle, and coacting therewith to form the complete ash tray and cigar extinguisher, and a spring pressed cigar holding and 125 130.

smothering means adapted to be pressed open of the jaws as they are progressively moved at its bottom to discharge its contents to successively greater opening positions through the chute and into the receptacle.

4. A combined ash tray and cigar extinguisher comprising an ash receptacle, a spring controlled means including a pair of plates normally in light bearing contact and coacting to provide an upwardly exposed opening therebetween for engaging the 5 of plates with their upper edges pivotally mounted and coacting to form a choke channel substantially V-shaped in vertical cross section, the upper portion of the plates being curved away from each other towards their pivot edges to form a wide-spreading 45 funnel and having their lower portions substantially straight and normally extending vertically and parallel to each other to form a narrow throat.
5. A cigar extinguisher comprising two pivotally mounted, spring pressed pressure plates coacting to form a choke-channel, normally 55 V-shaped in vertical cross section and adapted to receive the lighted end of a cigarette and reacting gently on the same to smother the light without crushing or otherwise materially distorting the configuration 60 of the lighted end of the cigarette.
6. A cigar extinguisher comprising a vertically extending chute including opposite outlining sides, a pair of pressure plates having their upper edges hinged to the opposite 65 sides of the chute and inclined downwardly and towards each other centrally of the chute to form a choke channel substantially V-shaped in cross section and spring disposed in the path of movement of the 70 plates to resist the spring movement of the plates when swinging away from each other.
7. A cigar extinguisher comprising a pair of jaws coacting to smother a cigar inserted between the same, and progressively acting 75 spring means for providing increasing degrees of resistance to the opening movement 80 of the jaws as they are progressively moved to successively greater opening positions.
8. A cigar extinguisher including a pair of plates with their upper edges pivotally mounted and coacting to form a choke channel substantially V-shaped in vertical cross section, the upper portion of the plates being curved away from each other towards their pivot edges to form a wide-spreading 85 funnel and having their lower portions substantially straight and normally extending vertically and parallel to each other to form a narrow throat.
9. A cigar extinguisher including a pair 90 of plates with their upper edges pivotally mounted and coacting to form a choke channel substantially V-shaped in vertical cross section, the upper portions of the plates being curved away from each other towards their pivot edges to form a wide-spreading 95 funnel and having their lower portions substantially straight and normally extending vertically and parallel to each other to form a narrow throat, and a pair of springs, one 100 for each plate, each disposed in the path of opening movement of its associated plate.
10. A cigar extinguisher including a pair of smothering jaws adapted to receive the lighted end of a cigar therebetween, a 105 spring for resisting the initial opening movement of one of said jaws, and a supplemental spring disposed in rear of the first named spring, adapted to add its resistance to that of the first named spring and coact therewith to resist a succeeding opening movement of the jaw.

Signed at New York in the county of New York and State of New York this 14th day of October, A. D. 1925.

REGINALD C. THOMAS.
